UNITED STATES PATENT OFFICE.

HERMAN MOSCHCOWITZ, OF NEW YORK, N. Y.

PATTERN FOR GARMENTS.

SPECIFICATION forming part of Letters Patent No. 350,073, dated September 28, 1886.

Application filed June 4, 1884. Serial No. 133,842. (No model.)

To all whom it may concern:

Be it known that I, HERMAN MOSCHCOWITZ, a citizen of the United States, residing at New York, in the county and State of New York, 5 have invented new and useful Improvements in Patterns for Garments, of which the following is a specification.

My invention relates to patterns, and has for its object to form a pattern which will 10 serve to display stays for garments and at the same time as a guide in placing the stays in their proper places in the garment; and to the foregoing ends it consists in a base, usually of paper, having printed or otherwise indicated 15 thereon the pattern of the whole or portion of a garment in which stays are usually employed, with the stay seams or pockets illustrated thereon and the stays secured thereto, so as to indicate where in the garment itself the 20 stays are to be applied, as will be hereinafter particularly described, and then specifically pointed out.

Figure 1 of the drawings is a side view of 25 part of a lady's waist-garment pattern, illustrating my invention. Fig. 2 is a side view of part of a waist-garment pattern basted together and having stays applied thereto.

The letter A designates the pattern of one-half of a lady's waist garment, looking at the 30 inside of any approved cut having printed or otherwise marked thereon stay seams or pockets B, usual in waist garments, the seam being illustrated as spread open, as usual, and held down by overcasting threads C.

For better illustrating the pattern, I represent a belt, D, secured thereto, as it frequently forms part of the waist, and for the same purpose have shown at *a* and *b* the seams as they appear when closed, forming the pockets or 35 darts. To each of the represented seams I affix a stay, which may be of any approved form. These stays are secured to the pattern by threads *c*, which, in addition to serving to hold the stays on the pattern, also serve to designate 40 the manner of securing said stays to the waist garment itself. These stays are attached to the patterns, with their upper ends at such varying heights as they will relatively bear to one another in the waist garment to which 45 they will be attached. While such heights may be indicated by observing the points at

which the stays are secured by the threads, still I prefer to designate such points by heavy black cross or transverse lines *d*, as illustrated. The stays will be of such varying lengths as 55 may be necessary and correspond in length to the length of the several seams from their cross-lines *d* to their lower ends, and while they may be secured to the pattern solely by threads *c*, still I prefer to further secure them 60 thereto by passing them through the pattern, as indicated by dotted lines in Fig. 1. When the pattern illustrates only a portion of the waist garment—as, for instance, one half of it, as shown in Fig. 1 of the drawings—there 65 are secured two stays to each seam, to which there will be attached only one stay each. The duplicate stays are intended for use on the opposite side on the other half of the waist garment, and will be applied thereto in the same 70 manner that they are attached to the side illustrated by the pattern. There is only one stay to each end seam, because the front seam represents the middle of the front of the garment, and the rear seam represents the middle of the back. When a full pattern is used, 75 only one stay will be secured to each seam of the pattern. The seams are preferably numbered from 1 upward in consecutive order, beginning with 1 at the front on each side 80 and running backwardly. In the drawings they are numbered from 1 to 7, and represent that number of parts in a garment.

In applying the stays to a waist from the pattern the stay taken from seam 1 will be 85 placed in the front dart. Those taken from seam 2 will be placed in the second darts from the front on both sides, and so on through the whole series.

Instead of making the pattern in the form 90 illustrated in Fig. 1, I may make it up in the form of a web cut into the parts of a waist garment, secured or basted together, with the pockets formed and the stays inserted and secured therein, the same as in the other case 95 already described herein, as shown in Fig. 2.

Having thus described my invention, what I claim is—

1. A pattern for waist garments, consisting of a base having marked thereon characters 100 representing the pockets in the garment and characters indicating the relative height of

- several stays to be attached thereto, and having secured to it stays in the relative positions which they are to be affixed to the garment, substantially as described.
5. 2. A pattern for waist garments, consisting of a base having marked thereon a series of characters consecutively designated, representing stay-pockets in the garment, and marked to designate the relative height of several stays as attached to the garment, and provided with a series of stays to be used on the garment, substantially as described.

3. A pattern for a waist garment, consisting of parts of a waist garment cut into the desired form, and connected together and having stays secured thereto in the positions they are to be when the garment is made up, substantially as described.

In testimony whereof I affix my signature in presence of two witnesses.

HERMAN MOSCHCOWITZ.
